CONTROLLABLE PITCH PROPELLER AND
THE LIKENicolaas E. Groeneveld Meijer, Schenectady,
N. Y., assignor to General Electric Company,
a corporation of New YorkApplication June 14, 1935, Serial No. 26,603
In Germany January 24, 1935

2 Claims. (Cl. 170—163)

This invention relates to controllable pitch propellers and the like and it has for an object the provision of a simple, reliable and efficient propeller of this character.

More particularly the invention relates to controllable pitch propellers in which the force for adjusting the pitch of the blades is produced by thermal energy responsive means, and a further object is the provision of a controllable pitch propeller in which the elongation of a simple metal body is utilized to adjust the pitch of the blades. Metallic bodies are peculiarly adapted for thermal adjusting elements for large propellers because of the large forces developed in response to thermal expansion. However, the elongation of a metal rod or sleeve is comparatively small even for a wide range of temperatures, and consequently a body of considerable length is required in order to obtain the necessary amount of adjusting motion. Metal bodies of great length, are inconsistent with the limited space of a propeller hub.

In order to eliminate the difficulties which are encountered in arranging a metal body with a sufficient thermal expansion in the propeller hub, the thermal-adjusting element is formed of a combination of bodies having high and low coefficients of thermal expansion. The individual metal bodies are connected in series in such a way that when heated the bodies with a high coefficient of thermal expansion have a motion which is opposite to that of the bodies with a low coefficient of thermal expansion. The adjusting elements resulting from this arrangement have a comparatively short length, so that they can be mounted in the propeller hub without difficulty. A particularly advantageous form of the invention results from an arrangement in which the metal bodies with the high and low coefficients of expansion are designed as sleeves or cylinders alternately telescoped one within another.

This invention constitutes an improvement of the controllable pitch propeller disclosed in application Serial No. 27,413, filed June 19, 1935 and assigned to the same assignee.

In illustrating the invention in one form thereof, it is shown as embodied in a thermal energy responsive bimetallic element for adjusting the pitch of the blades of an air craft propeller.

For a better and more complete understanding of the invention, reference should now be had to the following specification and to the accompanying drawing in which Fig. 1 is a sectional view of an embodiment of the invention, Fig. 2

is a fragmentary sectional view illustrating the operation and Fig. 3 is a view in elevation illustrating the arrangement of the propeller blades on the hub.

Referring now to the drawing, a hollow propeller hub 10 is secured to the flange 11 on the end of the motor shaft by suitable fastening means illustrated as bolts 12, 13.

A pair of propeller blades 8, 9 are mounted in the hub for rotation about their longitudinal axes. An adjusting disc 14 is secured to the root end of each blade and each disc is provided with an adjustment bolt. As shown, the disc 14 is provided with a bolt 15 and the disc for the opposite blade is provided with a similar adjustment bolt 16.

These bolts are arranged in slots in a yoke member 17 so as to cause the discs and the blades attached thereto, to rotate in opposite directions in response to straight line movement of the yoke. One end of the yoke is provided with a projection 17a which slides in a guideway 18, provided in an end plate 19 which is screwed into the hub member 10.

For the purpose of producing the necessary force for rotating the blades about their axes to adjust the pitch thereof, a thermal energy responsive bimetallic adjustment element 20 is provided which is heated by any suitable means, such for example as the electric heating element 21. This heating element is preferably arranged surrounding the bimetallic element, and is supplied with electric power from a suitable external source (not shown) to which it is connected by means of conductors 22 through slip rings 23 with which stationary brushes make contact. Suitable switching means are, of course, provided for completing and interrupting the connections between the heating element and source to control the pitch adjustment of the blades.

The bimetallic element 20 comprises a plurality of metal bodies, arranged side by side. In the specific form illustrated, a plurality of metal sleeves or cylinders 24, 25, 26, 27, 28, 29, 30 and 31 of different diameters are nested or telescoped one within another. The sleeves 24, 26, 28 and 30 are preferably made of a metal such as brass having a relatively high coefficient of thermal expansion whilst the alternate sleeves 25, 27, 29 and 31 are preferably made of a metal such as nickel steel having a relatively low coefficient of thermal expansion. Thus, the sleeves of relatively high and relatively low coefficient of thermal expansion are alternated with each other. The upper end of the outside sleeve 24 is rigidly

connected to the end wall 32 of the propeller hub 10. The ends of the sleeves 25, 27, 29 and 31 are connected as by welding or brazing to the ends of the sleeves 24, 26, 28 and 30 in such a manner that one end of a sleeve is connected only with the end of the adjacent outside sleeve, while the other end is connected only with the end of the adjacent inside sleeve. For example, the lower end of sleeve 24 is connected to the lower end of sleeve 25, and the upper end of the latter is connected to the upper end of sleeve 26. The sleeves are thus connected in series relationship with each other.

The upper end of the inside sleeve is connected with the rod 33 constituting an extension of the yoke 17, the upper end of which slides in a guide-way 34 in the end wall 32 of the hub.

When the heating element 21 is connected to the supply source to heat the adjusting element, the external sleeve 24 will elongate (downwardly in the drawing), since the upper end is supported by the solid end wall of the propeller hub. This downward elongation is transmitted by the sleeve 25 to the next sleeve 26, so that the latter is also moved downwardly. Since the sleeve 25 is made of metal having a relatively low coefficient of thermal expansion, it elongates slightly and in the opposite direction, owing to the connection of its lower end with the lower end of sleeve 24. As a result of the heating, the sleeve 26 has also elongated so that its entire adjusted path corresponds to the sum of the changes in lengths of the sleeves 24 and 26 less the slight change in length in the opposite direction of sleeve 25. The same applies for the subsequent sleeves 28 and 30 so that the adjusting element, after the heating is completed, will have assumed approximately the position which is shown in Fig. 2. This causes the adjusting yoke 40 to move toward the flange 11 and thus to cause the discs 14 to rotate and change the pitch of the propeller blades.

Although in accordance with the provisions of the patent statutes this invention is illustrated in the best form in which it is now contemplated carrying the invention into effect, it will be understood that the arrangement shown and described is merely illustrative and that the

invention is not limited thereto, since alterations and modifications will readily suggest themselves to persons skilled in the art without departing from the true spirit of this invention or from the scope of the annexed claims. 5

What I claim as new and desire to secure by Letters Patent of the United States is:

1. Pitch adjusting mechanism for a controllable pitch propeller having a hollow hub member and a plurality of propeller blades mounted thereon for rotation about their longitudinal axes comprising a plurality of spaced apart concentrically arranged cylindrical bodies having a relatively high coefficient of thermal expansion and a plurality of cylindrical bodies having a relatively low coefficient of thermal expansion concentrically arranged in the spaces between said high coefficient bodies, said high and low coefficient bodies being connected in series relationship with each other so that the bodies of 20 high and low coefficients change their lengths in opposite directions in response to change in temperature, said thermal expansion bodies being mounted within said hollow hub, means connecting said thermal expansion bodies to said 25 hub and to said blades, and means for supplying thermal energy to said bodies to produce a force for adjusting the pitch of the blades comprising an electric heating coil within said hub and means for supplying electric power to said coil. 30

2. Pitch changing mechanism for a controllable pitch propeller having a hollow hub member and a plurality of blades mounted thereon comprising means for supplying electric power to the interior of said hub, an electric heating element within said hub for converting electric energy into thermal energy, and a bimetallic element responsive to said thermal energy for producing a force to adjust the pitch of said blades comprising a plurality of metallic sleeves telescoped one within another, said cylinders being alternately of metal of relatively high and low coefficients of thermal expansion and connected together in series relationship so that said cylinders of high and low coefficients change length 45 in opposite directions and means connecting said bimetallic element to said hub and to said blades. 40
